(57) **CLAIM**

The ornamental design for a grommet, as shown and described.

DESCRIPTION

FIG. 1 is a perspective view from above of the grommet of the invention;

FIG. 2 is a top plan view of the grommet of FIG. 1;

FIG. 3 is a bottom plan view of the grommet of FIG. 1; and,

FIG. 4 is a front elevation view of the grommet of FIG. 1; the back and sides forming no part of the claimed design.

The broken lines are intended to show environmental structure and form no part of the claimed design.
